8 Claims. (Cl. 250—33)

The present invention relates to antennae and is especially concerned with a variable tuned vertical aerial having a grounded base directly connected with a concentric (coaxial) feeder or downlead.

It is well known that in the short wave field one may obtain relatively great wave-length ranges with an unvaried radiation diagram by using "crank" type antennae, wherein the aerial 10 is unreeled or paid out so as to result in a length of wire proportional to the wave length. Such antennae present a terminal or base impedance independent of the wave length.

It is particularly advantageous to make the 15 length of the aerial such that the same will be tuned to $\lambda/4$ or $3\lambda/4$ or $(2n+1)\lambda/4$, since in these instances the antenna impedance at the terminal point is purely ohmic. By connection with a concentric or coaxial cable or downlead whose characteristic impedance is equal to the terminal or 20 base resistance of the antenna, it is possible, as known from the prior art, to obtain a cable end free from reflection phenomena. Upon changes of wave length, the aerial wire must be paid out 25 or taken up. It has been suggested previously to place the reeling device in a "bulge" of the inner conductor of the coaxial cable or downlead, as described in my United States Patent 2,036,456, granted April 7, 1936, the outer conductor being 30 given a form so that the characteristic impedance of the line is preserved in order that by the aerial wire to be taken up no additional inductive or capacitive loads may be occasioned inadvertently at the end of the cable. This arrangement has 35 proved quite satisfactory where transmitters of small or medium power are dealt with, while difficulties are encountered whenever large powers are concerned. The reel to be accommodated in the interior of the cable, for constructional reasons, cannot be made of any desired size at all, and this places a limitation upon the maximum 40 diameter which the antenna conductor may have. However, where relatively large powers are concerned, quite apart from the current dissipated in 45 heat, this means high field intensities on the conductor surface so that, under certain circumstances, the breakdown field intensity in air may be exceeded. Where short waves are dealt with, there are then observed the typical "torches" es- 50 tablished by way of single-pole capacity coupling with ground and which, within a short time, lead to the destruction of the antenna, not to speak of the fact that also the cable may be endangered for similar reasons.

55 Stranded conductors when used for the outers,

even at the same diameter, are inferior to smooth tubes or wires because of their rough surface, so much more so as with repeated take-up and payout some of the small wires of the strand are caused to break so that they may be conductive 5 to corona.

Now, the present invention discloses methods of and means for overcoming the foregoing disadvantages in a very simple manner. Upon tuning to, say, $\lambda/4$ the variable antenna length must be 10 equal to $\frac{1}{4}(\lambda_{\text{max.}} - \lambda_{\text{min.}})$, if there is no capacitive end noise. Hence, if for instance, the wave 15 band of a transmitter is to extend from 14 to 40 meters, it will be seen that the length of the antenna must be capable of being varied a total of 15 6.5 meters.

Figs. 1 and 2 disclose two different embodiments of the invention.

Now, according to the invention, the antenna consists of a stable smooth conductor A (Fig. 1) 20 of adequate diameter which telescopes in the inner conductor D₁ of a concentric vertically mounted energy feeder or downlead D₁, D₂ having a characteristic impedance equal to the base end 25 or terminal impedance of the antenna, rather than of a thin reelable stranded conductor. In order to avoid burying this conductor part very deeply in the ground E, the antenna base point could also be placed above the ground by the creation of a counterpoise G_g disposed at a suitable 30 height (Fig. 1). In the embodiment here chosen, if the said counterpoise were mounted at an approximate height of 3½ meters, the vertical part of the conductor would have to be buried under the ground only about .3 of a meter, and this will 35 not be attended with serious difficulties in most instances. In order that bending of the antenna may be avoided, the antenna rod at its bottom end could be loaded by a weight M so that merely 40 tractile stresses are set up in case of changes in length. If the counterweight M is properly chosen, a motor provided for insuring adjustments would merely be called upon to cover the frictional losses; hence, the mechanical traction 45 could be chosen greater than is customary, and this would undoubtedly insure an improvement of the mechanical stability of the antenna.

In using greater wave-lengths or larger ranges or bands, the excavation work may be simplified by building the vertical part of the downlead 50 in the way shown in Fig. 2. The conductor arrangement in Fig. 2 requires that the innermost part of a concentric double line D₁ have the same characteristic impedance as the base or terminal point of the antenna. The inner conductor D₁ 55

brought upwards by a further outer tube D_{2a} which is also concentric and grounded. What thus results for the return are two paralleled concentric (or coaxial) lines D_1 and $D_2=D_{1a}$ against D_{1a} and D_{2a} against D_{2a} which should be so dimensioned that their parallel resistance will also become equal to the resistance W at the antenna base. Hence, the whole downlead or coaxial cable part which must be buried consists of a tube D_{2a} being smooth on the outside, which, in a way as known, for instance, from pinking wells, may be lowered into the ground E . Connection between cable K and the inner conductor K_1 and the outer conductor K_a is then effected at the upper end of the energy line D_2 at some suitable and easily accessible point.

In order to avoid great lengths of vertical energy feeder leads where the wave length ranges or the wave lengths are still greater, it is practical to build the antenna rod A of several telescoping tube pieces. The antenna rod A , which would be plunged to different depths into the inner conductor D_1 of the downlead D in the presence of different wave lengths, would also allow of tele-indication of the effective antenna length either by mechanical or electrical means, for example, by arranging for the traction rope Z which connects the antenna rod A and the antenna counterweight M with the mechanical balancing weight M_g to pass over a pulley which in some convenient way drives an indicator or pointer device.

The invention, it will be understood, is not limited to the exact embodiments hereinbefore described and illustrated, since various modifications can be made without departing from the spirit and scope thereof.

It is to be distinctly understood that the term "odd multiple" used in the specification and appended claims is intended to mean any odd multiple including one.

What is claimed is:

1. In combination, a vertical antenna tuned to have a length equal to an odd multiple of a quarter of the operating wave, a variable length support attached to the upper end of said antenna, a weight attached to the lower end of said antenna, a concentric conductor system having inner and outer tubular conductors located beneath said antenna, said weight being free to move within said inner conductor as said antenna is varied in length from said upper end, said inner conductor being in electrical contact with said antenna.

2. In combination, a vertical antenna tuned to have a length equal to an odd multiple of a quarter of the operating wave, a variable length support attached to the upper end of said antenna, a weight attached to the lower end of said antenna, a hollow vertical conductor located directly beneath said antenna, said weight being located and able to move within said hollow conductor as said antenna is varied in length, and a counterpoise comprising a horizontal conducting element attached substantially to the upper end of said hollow conductor.

3. In combination, a variable length antenna which is vertical for at least the lower portion of its length, a weight attached to the lower end of said antenna, a hollow vertical conductor

located directly beneath said antenna, said weight being located and able to move within said hollow conductor as said antenna is varied in length, and a counterpoise comprising a horizontal conducting element attached substantially to the upper end of said hollow conductor.

4. In combination, a variable length antenna adapted to be tuned to an odd multiple of a quarter of the operating wave and being vertical for at least the lower portion of its length, a weight attached to the lower end of said antenna, a hollow vertical conductor located directly beneath said antenna, said weight being located and able to move within said hollow conductor as said antenna is varied in length, said lower portion of said antenna above said weight being in electrical contact with said hollow conductor.

5. In combination, a vertical antenna tuned to have a length equal to an odd multiple of quarter of the operating wave, a variable length support attached to the upper end of said antenna, a weight attached to the lower end of said antenna, a concentric conductor system having inner and outer tubular conductors located beneath said antenna, said weight being free to move within said inner conductor as said antenna is varied in length from said upper end, said inner conductor being in electrical contact with said antenna, said concentric conductor system having only a portion thereof extending above ground, the total length of said antenna outside and within said concentric conductors being capable of being varied a distance difference between the largest and smallest wavelengths to which the antenna is adapted to be tuned, and a concentric energy feeder line coupled above ground to said concentric conductor system.

6. In combination, a vertical antenna tuned to have a length equal to an odd multiple of a quarter of the operating wave, a variable length support attached to the upper end of said antenna, a weight attached to the lower end of said antenna, a concentric conductor system having inner and outer tubular conductors located beneath said antenna, said weight being free to move within said inner conductor as said antenna is varied in length from said upper end, said inner conductor being in electrical contact with said antenna, and a counterpoise connected to said outer conductor.

7. An antenna system in accordance with claim 5, including a counterpoise connected to the upper part of said outer tubular conductor.

8. In combination, a vertical antenna tuned to have a length equal to an odd multiple of a quarter of the operating wave, a variable length support attached to the upper end of said antenna, a weight attached to the lower end of said antenna, a concentric conductor system having inner and outer tubular conductors located beneath said antenna, said inner and outer tubular conductors being folded back for a substantial portion of said concentric conductor system, said weight being free to move within said inner conductor as said antenna is varied in length from said upper end, said inner conductor being in electrical contact with said antenna, and a feeder coupled to said folded back portion.

WERNER BUSCHBECK.
